[57] CLAIM

The ornamental design for a fishing rod including an integrally formed handle, as shown and described.

DESCRIPTION

FIG. 1 is a left side elevational view of a fishing rod including an integrally formed handle according to my new design, the right side elevational view being the mirror image thereof;

FIG. 2 is an enlarged left side elevational view, partially broken away, of the fishing rod and integrally formed handle;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.
